Primary Examiner — John R Yeh(74) *Attorney, Agent, or Firm* — The Roy Gross Law Firm, LLC; Roy Gross(57) **CLAIM**

The ornamental design for squeegee, as shown and described.

DESCRIPTION

FIG. 1 is a bottom view of a squeegee in accordance with the new design;

FIG. 2 is a front view thereof;

FIG. 3 is a top view thereof;

FIG. 4 is a rear view thereof;

FIG. 5 is a side view thereof;

FIG. 6 is a front perspective view thereof; and,

FIG. 7 is a bottom perspective view thereof.

The broken lines in the figures depict portions of the squeegee that form no part of the claimed design.

1 Claim, 2 Drawing Sheets(56)
